UNITED STATES PATENT OFFICE

164,261

HARD SURFACE RUG OR THE LIKE

Arthur Post and William Lynen, New York, N. Y.,
assignors to Bona Fide Mills, Inc., New York,
N. Y., a corporation of Maine

Application October 4, 1950, Serial No. 12,449

Term of patent 14 years

(Cl. D92—21)

To all whom it may concern:

Be it known that we, Arthur Post, a citizen of the United States of America, and a resident of New York city, county and State of New York, and William Lynen, a citizen of the United States of America, and a resident of New York city, county of Queens and State of New York, have invented a new, original, and ornamental Design for a Hard Surface Rug or the like, of which the following is a specification, reference being had to the accompanying drawings forming part thereof, of which:

The single figure is a top plan view of the hard surface rug showing our new design.

We claim:

The ornamental design for a hard surface rug or the like, as shown.

ARTHUR POST.
WILLIAM LYNEN.
